UNITED STATES PATENT OFFICE

2,400,607

TREATMENT OF TALL OIL

Ernest Segesemann, Newark, N. J., assignor to
National Oil Products Company, Harrison,
N. J., a corporation of New Jersey

No Drawing. Application January 1, 1942,
Serial No. 425,347

19 Claims. (Cl. 260—97.5)

This invention relates in general to the production of valuable products from tall oil, and more particularly to a process of separating tall oil into its main constituents; i. e. fatty and resinic substances. The present invention is especially directed to the recovery of valuable products from tall oil in the course of which recovery the tall oil is subjected to both hydrogenation and esterification, my copending application Serial No. 309,703, now Patent No. 2,305,498, of which this is a continuation in part being directed to a similar process during which the tall oil is subjected to hydrogenation to varying extents without being subjected to any extensive esterification; my copending application Serial No. 425,348, filed herewith, now Patent No. 2,373,979, being directed to a similar process in which the tall oil is esterified to varying extents without being subjected to any extensive hydrogenation; and my copending application Serial No. 425,346, filed herewith, now Patent No. 2,373,978, being directed to similar processes in which the tall oil is neither esterified nor hydrogenated to any considerable extent.

"Tall oil" or "talloel," which literally means "pine oil," is the resinous and fatty by-product obtained chiefly in the production of paper pulp from resin-bearing woods by the so-called sulphate process. In the sulphate process wood is digested with an alkaline liquor containing sodium sulphate, during which process tall oil accumulates in the form of its sodium soap on the surface of the waste liquor. The main constituents of this oil, after acidification, comprise resinic acids and fatty acids, the latter consisting mainly of oleic, linoleic, and linolenic acids, each of which are valuable commodities in substantially pure form. Various processes have been proposed in an attempt to effect separation of tall oil into its main constituents, i. e. fatty acids and resinic acids. One process comprises esterifying the fatty acids in tall oil with a low boiling alcohol and separating the resulting fatty ester from the free rosin acids by distillation or by alkali extraction. Another known process comprises esterifying the fatty acids with a polyhydric alcohol and distilling off the resinic acids. According to another process, both the fatty acids and the resinic acids are esterified with a polyhydric alcohol and the resin esters are then catalytically split and the liberated resinic acids distilled off. While the foregoing and other known processes have been employed with varying degrees of success, they all exhibit certain disadvantages, primarily in that only

partial separation is effected. Moreover, the fatty acid fraction obtained by these processes, consisting mainly of a mixture of oleic, linoleic and linolenic acids, is not particularly suitable for a wide variety of industrial uses. Usually having an iodine value of about 120 to 130, this fatty acid fraction (or its esters) shows some drying properties, but these drying properties are not pronounced enough for a drying oil of good quality. On the other hand, this fatty acid fraction is too highly unsaturated to find extensive application in some of the largest fat-consuming industries, namely the soap industry, or in the manufacture of specialties for the textile and tanning trades, the bulk of fats used in these industries being of more highly saturated type.

The general object of this invention is to obviate the foregoing and other disadvantages.

20 A specific object of the invention is to provide an improved and more efficient process for separating tall oil into its main constituents.

A further object of the invention is to provide an improved process for separating tall oil into 25 its constituents and recovering the fatty constituents thereof in a more saturated form so that the same can be adapted to a wide industrial use.

Still another object is to recover from tall oil 30 a more highly unsaturated fraction suitable for many technical applications.

Other objects will in part be obvious and will in part appear hereafter.

The foregoing and other objects are accomplished according to the broader aspects of the 35 invention whereby tall oil is treated with esterifying agents to convert the fatty acids therein to the form of esters, and is further subjected to hydrogenation to decrease the unsaturation of the fatty materials. The esterified and hydrogenated tall oil is dissolved in a suitable solvent and subjected to temperatures sufficiently low to effect precipitation of a certain fraction of, or all of, the fatty esters thereof, followed by removal of 45 said precipitated fraction by filtration or centrifugation or by any other known means of separating an insoluble solid from a liquid. The resinic constituents remaining in the solvent may be recovered by distilling off the solvent. The tall 50 oil esters employed in accordance with the process of the invention may be derived from either crude or distilled tall oil and they may be subjected to varying degrees of hydrogenation before being subjected to the chilling and separating 55 steps. If the esterified tall oil used in the above

mentioned process is of the crude or distilled type and has not been subjected to very extensive hydrogenation, the filtrate obtained upon separation of the precipitated fatty acids will also contain fatty esters of the more highly unsaturated type, mostly linoleic and linolenic acids. These higher unsaturated fatty acids may then be separated from the rosin by esterification followed by alkali extraction of the rosin, or by methods disclosed in my copending applications, Serial Nos. 217,974 and 303,535, filed July 7, 1938, and November 9, 1939, respectively, now Patents Nos. 2,199,653 and 2,278,674. Alternatively, the mixture of rosin constituents and higher unsaturated fatty esters may be used as such in the preparation of other products such as drying oils, which is to be the subject matter of another application. If the tall oil esters are hydrogenated to a degree where at least all the highly unsaturated fatty substances have been converted to the oleic compounds, the fatty fraction can be completely separated from the resinic substances by cooling and filtration alone. A lesser degree of hydrogenation will result in a somewhat diminished yield of esters, the more unsaturated esters tending to remain in solution.

This invention accordingly comprises the several steps and the relation of one or more of such steps with respect to each of the others thereof, which will be exemplified in the process herein-after disclosed, and the scope of the invention will be indicated in the claims.

In carrying out the process of the invention, the first step involves the treatment of tall oil to convert the fatty acids therein to the form of esters. Preferably the fatty acids are converted to esters of monohydric alcohols, rather than polyhydric, since otherwise mixed fatty and rosin esters may be formed and a less sharp separation of the fatty from the resinic constituents may result. Preferably also, for best results, the alcoholic constituents introduced by esterification should be derived from the lower alcohols containing from 1 to 5 carbon atoms. The esterification may be carried out to varying extents; for instance, only the fatty acids in the tall oil may be converted to the form of esters, or, alternatively, a greater or lesser proportion of the rosin acids may likewise be esterified. Any suitable esterification reagents and processes may be employed, for instance refluxing the tall oil with an appropriate alcohol in the presence of an esterification catalyst, or treating the tall oil at high temperatures and pressures with an alcohol.

After the esterification step, the tall oil fatty esters are subjected to partial or complete hydrogenation, depending on the type of fatty products desired. For example, partial hydrogenation of the fatty esters may be carried on to convert a greater or lesser proportion of the linoleic and linolenic esters to oleic esters, whereby these esters will constitute a large portion of, or substantially all of, the fatty esters. On the other hand hydrogenation may be carried on further to decrease the degree of unsaturation in the resulting fatty esters, whereby all or substantially all the fatty esters will be converted into stearic esters or a mixture having an average iodine value of about 10 or less.

The esterified and hydrogenated tall oil is next dissolved in a suitable solvent therefor which is characterized by the property of retaining the resinic acids or derivatives thereof in solution at low temperatures and permitting the fatty acid derivatives thereof to precipitate out at low

temperatures. Examples of such solvents include, inter alia, petroleum hydrocarbons, such as, gasoline, kerosene, heptane, mineral spirits, etc.; aromatic hydrocarbons, such as, benzene, toluene, xylene, etc.; alcohols, such as ethyl alcohol, methyl alcohol, isopropyl alcohol, etc.; ketones, such as acetone, ethyl methyl ketone, cyclohexanone, etc.; chlorinated hydrocarbons, such as, ethylene dichloride, trichlorethylene, etc.

The steps of esterifying, hydrogenating and dissolving the tall oil in the solvent have been described above as following each other in that sequence. Obviously, these steps may be carried out in any other sequence; the dissolving of the tall oil in the solvent may precede the esterification and hydrogenation steps, the hydrogenation may precede the other two steps, and so on in the various possible permutations, these steps being additive and resulting in a solution of esterified and hydrogenated tall oil in the solvent, which solution may be chilled to recover the desired esters. Accordingly in the specification and claims to follow, it is to be understood that the recitation in any order of these steps is to be construed to mean the combination of these steps indifferently in any order, unless the contrary is explicitly indicated.

After there has been obtained the desired solution of the esterified and hydrogenated tall oil in a suitable solvent, the temperature of the solution is decreased to obtain the desired degree of precipitation of fatty esters thereof. By actual experiment, a temperature range of about 5° C. to -70° C. will accomplish this result. It is obvious, of course, that temperatures outside of this range may also be operative to carry out the objects of the invention. The degree of cooling will be varied according to the nature of the solvent used and according to the form in which the fatty and resinous materials occur. The degree of cooling will be further varied according to the product desired, lower temperatures being required when it is desired to remove a larger proportion of the esters from the solution. Moreover, the degree of hydrogenation of the tall oil constituents will play an important role in determining the time and temperature under which precipitation will be effected. The precipitated fatty esters are removed from the solvent solution by any suitable means including centrifugation and filtration. The precipitated products after removal are preferably washed with a suitable solvent, i. e. the same solvent as used in the process, and preferably at substantially the same temperature at which the precipitating operation was carried out.

For a fuller understanding of the nature and objects of the invention, reference should be had to the following examples, which are given merely to illustrate the invention and are not to be construed in a limiting sense.

Example I

The fatty acids in 100 gms. of distilled tall oil were esterified by refluxing for three hours with 50 ml. of methanol and 2 gms. of sulphuric acid. The product (after distilling off the excess alcohol and washing out the sulphuric acid) was composed of 70% methyl esters of the fatty acids, 6% of unsaponifiable matter and 24% of free rosin. This mixture was then hydrogenated for 2 hours at a pressure of 140 atmospheres and at a temperature of 170° C. in the presence of 3% of nickel as a catalyst.

100 gms. of the hydrogenated product which

had an iodine value of 25.4 were dissolved in 750 ml. of acetone and cooled at -18° C. overnight. The precipitated esters of the fatty acids were then filtered off and washed four times each, with 70 ml. portions of acetone cooled to -18° C. The filter cake consisting of the methyl esters of the fatty acids was a pure white solid below room temperature and upon analysis it showed a rosin content of .32% and an iodine value of 9.7%.

The rosin was then recovered from the filtrate by distilling off the acetone.

Example II

100 gms. of the methyl esters of tall oil, which were prepared by completely esterifying tall oil under pressure with methanol, were hydrogenated to an iodine value of 18.5. The hydrogenated product was then dissolved in 600 ml. of ethylene chloride and cooled at -18° C. for 12 hours. The solid methyl esters of the fatty acids were then filtered off and washed several times with cold ethylene chloride. The methyl esters thus recovered had a rosin content of 1.9%.

The methyl abietate in the filtrate was then recovered by distilling off the solvent.

Example III

In a closed vessel which was provided with a reflux condenser, 100 gms. of distilled tall oil having a rosin content of 35% were heated with 11 gms. of anhydrous glycerol at such a rate that the temperature rose gradually to 280° C. during six hours. The triglyceride of tall oil thus obtained (having an acid value of 3.0) was then hydrogenated at a pressure of 7 atmospheres and at a temperature of 150° C. to 160° C. using 2% of nickel as a catalyst. The hydrogenated product had an iodine value of 46.0.

100 gms. of the hydrogenated product were dissolved in 700 ml. of gasoline and cooled to -5° C. for 6 hours. The solid fraction was removed by filtration and washed with fresh gasoline. The product thus obtained was a white solid containing 18.5% of combined rosin.

Upon distillation of the gasoline from the filtrate, a heavy viscous fluid was obtained consisting of mixed triglycerides high in combined rosin content.

Since certain changes may be made in carrying out the above process without departing from the scope of the invention, it is intended that all matter contained in the above description shall be interpreted as illustrative and not in a limiting sense.

It is also to be understood that the following claims are intended to cover all the generic and specific features of the invention herein described, and all statements of the scope of the invention, which as a matter of language might be said to fall therebetween.

Having described my invention, what I claim as new and desire to secure by Letters Patent is:

1. A process of treating tall oil to separate a fatty fraction therefrom which comprises esterifying the fatty acids in tall oil with a monohydric alcohol, hydrogenating the fatty acid esters in the esterified mixture, decreasing the temperature of the resulting mass in the presence of a solvent to effect precipitation of fatty acid esters and removing the precipitated fatty acid esters from the remaining solution.

2. Process for treating tall oil which comprises, in indifferent order, hydrogenating the fatty radicals in said oil and esterifying the same with a lower alcohol; thereafter lowering the tem-

perature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

3. Process for treating tall oil which comprises, in indifferent order, hydrogenating the fatty radicals in said oil and esterifying the same with a monohydric alcohol; thereafter lowering the temperature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

4. Process for treating tall oil which comprises, in indifferent order, hydrogenating the fatty radicals in said oil and esterifying the same with methanol; thereafter lowering the temperature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

5. Process for treating tall oil which comprises, in indifferent order, hydrogenating the fatty radicals in said oil and esterifying the same with a polyhydric alcohol; thereafter lowering the temperature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

6. Process for treating tall oil which comprises, in indifferent order, hydrogenating the fatty radicals in said oil and esterifying the same with glycerol; thereafter lowering the temperature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

7. Process for treating tall oil which comprises, in indifferent order, hydrogenating the fatty radicals in said oil to convert them at least to the oleic and esterifying the same with a lower alcohol; thereafter lowering the temperature of the esterified and hydrogenated tall oil in the presence of a solvent so as to effect a separation thereof into a fatty ester fraction insoluble in said solvent at the lowered temperature and a solution of constituents soluble in said solvent at the lowered temperature; and lastly separating the insoluble fatty ester fraction from said solution.

8. Process for treating tall oil which comprises, in indifferent order, hydrogenating the fatty radicals in said oil to convert them at least to the oleic and esterifying the same with a monohydric alcohol; thereafter lowering the tem-
